(57) **ABSTRACT**

A method of making a slider includes the steps of laminating the bottom-facing surface of a third layer to the upper-facing surface of a fourth layer, laminating the bottom-facing surface of a second layer to the upper-facing surface of the third layer in a heat-compression mold, heat-pressing the combined second, third and fourth layers in the mold to form a desired shape, and heat pressing a first layer on top of the second layer inside the mold.

FIG. 2

FIG 4B

FIG 4A

FIG. 6

FIG. 8

FIG. 9

1

METHOD OF MAKING A SLIDER

BACKGROUND OF THE INVENTION

1. Field of the Invention

The present invention relates to a slider that can be used as a body board, a snow board, a grass sliding board, a sand sliding board, or other board.

2. Description of the Prior Art

Traditional sliders have been used as snow boards, and have increased in popularity as more and more people are seeking snow-related outdoor activities. Examples of such traditional sliders are illustrated in Pub. No. US2003/0224675 (Yeh) and U.S. Pat. No. 4,850,913 (Szabad, Jr.). U.S. Pat. No. 5,275,860 (D'Luzansky et al.) and U.S. Pat. No. 5,114,370 (Moran) illustrate body boards that can be used for water sports.

All of these known sliders and body boards are essentially provided in the form of a simple board having a generally flat upper surface and a generally flat and smooth lower surface. One reason why these sliders have a generally flat and smooth lower surface is because these sliders are typically made by laminating one or more layers of material (e.g., polyethylene) on to a foam core. As a result, it is very difficult and expensive to form a lower surface having a shape and a surface that is anything other than flat and smooth. In addition, the use of this manufacturing method also means that the handles provided for these sliders must be made as separate components and then attached (e.g., with a snap-fit top and bottom handle housing) to the slider.

When these sliders are used as snow boards, the flat and smooth lower surface provides little friction or resistance, so that the user is not able to control or maneuver the slider. As a result, these sliders tend to spin in the snow if an unexpected force is imparted on to any part of the slider. As another result, the user positioned on and moving with the slider is unable to turn or otherwise maneuver the slider.

Therefore, there still remains a need for a slider that overcomes the drawbacks set forth above.

SUMMARY OF THE DISCLOSURE

It is an object of the present invention to provide a slider that allows the user to control and maneuver the slider during use.

It is another object of the present invention to provide a slider that has a traction system provided on its bottom surface for allowing the user to control and maneuver the slider during use.

It is another separate and independent object of the present invention to provide a slider that has handles built into the slider without using separate handles that must be attached to the slider.

In order to accomplish the objects of the present invention, the present invention provides a method of making a slider having a first upper layer, a second intermediate layer, a third intermediate layer, and a fourth bottom layer. The method includes the steps of laminating the bottom-facing surface of the third layer to the upper-facing surface of the fourth layer, laminating the bottom-facing surface of the second layer to the upper-facing surface of the third layer in a heat-compression mold, heat-pressing the combined second, third and fourth layers in the mold to form a desired shape, and heat pressing the first layer on top of the second layer inside the mold.

2

BRIEF DESCRIPTION OF THE DRAWINGS

FIG. 1 is a perspective view of a slider according to one embodiment of the present invention.

5 FIG. 2 is a cut-away exploded perspective view illustrating the layers of the slider of FIG. 1 according to one embodiment of the present invention.

FIG. 3 is a cut-away assembled perspective view of the layers of FIG. 2.

10 FIGS. 4A and 4B are enlarged cross-sectional views of the section A of FIG. 3.

FIG. 4C is a cross-sectional view taken along line C-C in FIG. 1.

15 FIG. 5 is a bottom perspective view of the traction system of the slider of FIG. 1.

FIG. 6 is a cross-sectional view of the traction system of FIG. 5 taken along line 6-6.

20 FIG. 7 is a perspective cross-sectional view of a slider according to another embodiment of the present invention where graphics are incorporated on the bottom surface thereof.

FIG. 8 is a perspective cross-sectional view of the slider of FIG. 7 illustrating modifications made thereto.

25 FIG. 9 is a perspective cross-sectional view of a slider according to another embodiment of the present invention where graphics are incorporated on the top surface thereof.

FIG. 10 is a perspective cross-sectional view of the slider of FIG. 9 illustrating modifications made thereto.

30 FIG. 11 is a perspective cross-sectional view of a slider according to another embodiment of the present invention where graphics are incorporated on the top and bottom surfaces thereof.

FIG. 12 is a perspective cross-sectional view of the slider of FIG. 11 illustrating modifications made thereto.

DETAILED DESCRIPTION OF THE PREFERRED EMBODIMENTS

The following detailed description is of the best presently 40 contemplated modes of carrying out the invention. This description is not to be taken in a limiting sense, but is made merely for the purpose of illustrating general principles of embodiments of the invention. The scope of the invention is best defined by the appended claims.

45 FIG. 1 illustrates a slider 20 which has a board 22 which includes a bottom surface 24 and a top surface 26 (also known as a deck surface). Openings 28 can be provided in the board 22 at any desired location to act as handles. The board 22 can be provided in any shape or size.

50 FIGS. 2-6 illustrate one embodiment for the board 22. The board 22 can be made up of a first layer 32, a second layer 34, a third layer 36 and a fourth layer 38 that are a laminated together, from top to bottom, in this order. The first layer 32 is preferably a low-density polyethylene (LDPE) or cross-poly-

55 ethylene (XPE) material having a thickness between 2 mm and 5 mm. The second layer 34 is essentially the core of the board 22, and is preferably a LDPE material having a density between 30 KG to 60 KG per 1 m³. Since the second layer 34 is essentially the core of the board 22, it can have any desired thickness depending on how thick the board 22 is intended to be. The third layer 36 is preferably a LDPE or XPE material having a thickness between 2 mm and 5 mm. The fourth layer 38 is a mixture of a LDPE and a high density polyethylene (HDPE) that has been extruded together. The LDPE can be 30% of the mixture, with the HDPE being 70% of the mixture, or the HDPE can be 30% of the mixture, with the LDPE being 70% of the mixture. Thus, if the mixture includes more

60 65

HDPE, the fourth layer **38** will be made of a harder material than if the mixture includes more LDPE.

As non-limiting examples, a HDPE material according to the present invention would have a specific gravity of less than 0.94, while a LDPE material according to the present invention would have a specific gravity of 0.94 or more.

The density of the material of the first layer **32** is preferably greater than the density of the material for the second layer **34**, and can have the same or greater density than the material for the third layer **36**. The density of the material of the third layer **36** is preferably greater than the density of the material for the second layer **34**. In other words, the density of the material for the second layer **34** is the smallest because the second layer **34** acts as the core. In addition, the density of the material for the fourth layer **38** is greater than the densities of the materials for the other layers **32, 34, 36** because the fourth layer **38** represents the bottom of the board **22** and therefore needs to be stronger.

The board **22** can be formed according to the following process:

1. The fourth layer **38** is formed by a liquid extrusion process.
2. The bottom-facing surface of the third layer **36** is heat laminated to the upper-facing surface of the fourth layer **38**. This can be accomplished by applying (e.g., sticking) the third layer **36** to the fourth layer **38** while the fourth layer **38** is still wet from its liquid extrusion, and then allowing the layers **36** and **38** to dry and bond together.

3. The combined third and fourth layers **36** and **38** are then heat laminated with the second layer **34** in a heat compression mold. Specifically, the bottom-facing surface of the second layer **34** is heat laminated to the upper-facing surface of the third layer **36**. The mold is formed in any desired shape, and is therefore used to shape the board **22**.

4. The layers **34, 36** and **38** are heat-pressed in the mold to form the desired product shape.

5. The mold is then opened, and the first layer **32** is placed into the mold and heat-pressed on top of the upper-facing layer of the second layer **34**.

6. The mold is opened and excess material is trimmed away from the edges in the manner illustrated in FIGS. 4A and 4B.

As shown in FIG. 4A, a portion **44** of the edge **42** of the first layer **32** may not be laminated to the second layer **34** because of the curvature of the other layers **34, 36** and **38**. This portion **44** is therefore an excess portion that can be manually cut (e.g., by a blade), or cut by a machine that has a blade. The resulting edge **46** of the first layer **32** is then heat sealed to the fourth layer **38**, as shown in FIG. 4B.

The molding of the layers **34+36+38** to the first layer **32** allows the board **22** to be formed with any desired cross-sectional shape. For example, as shown in FIG. 6, the board **22** can be formed to have (i) two side walls **70** and **72** that enclose an interior space **74**, and (ii) a traction system as described below. In addition, the molding of the layers **34+36+38** to the first layer **32** allows the board **22** to be formed with openings **28** that can be used as handles by a user for gripping purposes. To form handles, the edges of the first layer **32** can be processed in the same manner as shown in FIGS. 4A and 4B. Specifically, as shown in FIG. 4C, a portion **48** of the edge **50** of the first layer **32** may not be laminated to the second layer **34** because of the curvature of the other layers **34, 36** and **38**. This portion **48** is therefore an excess portion that can be manually cut (e.g., by a blade), or cut by a machine that has a blade. The resulting edge **51** of the first layer **32** is then heat sealed to the fourth layer **38**. This can be done on both sides of each opening **28**.

A traction system can be provided on the bottom of the board **22** to allow the user to control and maneuver the slider during use. Referring to FIGS. 5 and 6, the traction system can include a generally V-shaped central tracking edge **52** for speed and directional control, a braking system **54** that is provided with the central track system **52** for stopping the slider **20**, a recessed straight edge **56** provided on either side of the central tracking edge **52** for gripping the snow, a straight edge **58** exterior to each recessed straight edge **56** for speed and directional control, and a parabolic edge **60** positioned exterior to each straight edge **58** to assist in turning of the slider **20**. The edges **52** and **58** are raised areas on the board **22** that are capable of digging into the snow when the board **22** is in use. The raised areas mean that there is minimal surface area in contact with the snow (similar to an aerofoil boat concept), thereby creating less drag to facilitate higher speeds. In addition, the narrowness of the raised areas provides good directional control in the same manner that a surfboard fin accomplishes this function. The recessed straight edges **56** are two channels which fill with snow when the board **22** travels downhill, thereby helping the board **22** to maintain direction and improve grip. The parabolic edge **60** has a curvature which allows the board **22** to turn in the direction of the curvature. All of these edges **52, 56, 58** and **60**, and the braking system **54**, are pre-formed in the mold, so that the board **22** and its bottom surface **24** can be formed by the mold with these edges **52, 56, 58** and **60**, and the braking system **54** incorporated therein. The braking system **54** is formed by a plurality of cut-outs **62** in the V-shaped central tracking edge **52**. These cut-outs **62** fill with snow when the board **22** turns backwards, thereby slowing the board **22** to fulfill the braking function.

The embodiment shown and illustrated in FIGS. 1-6 is of a slider **20** that does not have any graphics or patterns printed on the bottom surface **24** or the top surface **26**. FIG. 7 illustrates how graphics can be provided on the bottom surface **24** of the slider **20** according to one embodiment of the present invention. A printing layer **82** and a binding layer **84** can be provided between the third layer **36** and the fourth layer **38**. The process for forming the slider shown in FIG. 7 is as follows.

- 7a. A graphics pattern **86** can be formed (e.g., by printing) on the bottom-facing surface of the printing layer **82**. The graphics pattern **86** can be ink that is printed to the bottom-facing surface of the printing layer **82** using techniques known in the art, and represents the desired graphics. The printing layer **82** can be embodied in the form of a LDPE material having a thickness ranging from 0.04 mm to 0.08 mm.

- 7b. The upper-facing surface of the printing layer **82** is heat laminated to the bottom-facing surface of the binding layer **84**. The binding layer **84** can be embodied in the form of a PE or LDPE material having a thickness ranging from 0.02 mm to 0.04 mm.

- 7c. The upper-facing surface of the binding layer **84** of the combined printing layer **82** and binding layer **84** (with the graphics pattern **86** printed on the bottom facing surface of the printing layer **82**) is heat laminated to the bottom-facing surface of the third layer **36**.

- 7d. The bottom-facing surface of the printing layer **82** (i.e., the surface on which the graphics pattern **86** is printed) is heat laminated to the upper-facing surface of the fourth layer **38**.

- 7e. The process then follows the same steps as steps 3-6 set forth above in connection with the embodiment of FIGS. 1-6, with the binding layer **84** and the printing layer **82** sandwiched between the third and fourth layers **36** and **38**.

FIG. 8 illustrates a modification that can be made to the slider of FIG. 7, where the binding layer **84** is omitted. The

binding layer is not essential, and functions to strengthen the bonding between the layers **82** and **36**. Thus, where it is desired to reduce manufacturing costs, the binding layer **84** can be omitted. The process for making the slider of FIG. 8 is the same as described above for the slider of FIG. 7, except that the upper-facing surface of the printing layer **82** is directly heat-laminated to the bottom-facing surface of the third layer **36**.

FIG. 9 illustrates how graphics can be provided to the top surface **26** of the slider **20** according to one embodiment of the present invention. A printing layer **182**, a binding layer **184** and a protection layer **188** can be provided above the first layer **32**. The process for forming the slider shown in FIG. 9 is as follows.

9a. A graphics pattern **186** can be formed (e.g., by printing) on the upper-facing surface of the printing layer **182**. The graphics pattern **186** can be ink that is printed to the upper-facing surface of the printing layer **182** using techniques known in the art, and represents the desired graphics. The printing layer **182** and the binding layer **184** can be identical to the printing layer **82** and the binding layer **84** described above in connection with the slider of FIG. 7.

9b. The protection layer **188** is heat laminated to the upper-facing surface of the printing layer **182** (i.e., the surface on which the graphics pattern **186** is printed). The protection layer **188** can be embodied in the form of a transparent polyethylene layer having a thickness ranging from 0.02 mm to 0.05 mm.

9c. The bottom-facing surface of the printing layer **182** of the combined protection layer **188** and printing layer **182** is positioned above the upper-facing surface of the binding layer **184**, and the bottom-facing surface of the binding layer **184** is positioned above the upper-facing surface of the first layer **32**, and these layers **188+182+184+32** are simultaneously heat laminated together.

9d. The process then follows the same steps as steps **1-6** set forth above in connection with the embodiment of FIGS. **1-6**, with the protection layer **188**, the binding layer **184** and the printing layer **182** laminated to the top of the first layer **32**. Specifically, in step **5** of the embodiment of FIGS. **1-6**, when the mold is opened, the combined layers **188, 184, 182** and **32** are placed into the mold and heat-pressed on top of the upper-facing layer of the second layer **34**.

FIG. 10 illustrates a modification that can be made to the slider of FIG. 9, where the binding layer **184** is again omitted. The process for making the slider of FIG. 10 is the same as described above for the slider of FIG. 9, except that the bottom-facing surface of the printing layer **182** is directly heat-laminated to the upper-facing surface of the first layer **32**.

The construction and processes illustrated in connection with FIGS. **7-10** can be combined to provide graphics on both the bottom surface **24** and the top surface **26** of the slider **20**. For example, FIG. 11 illustrates the layers for a slider that incorporates the principles illustrated in FIGS. **7** and **9**. The same numeral designations utilized in the embodiments in FIGS. **7** and **9** are also used in FIG. 11, since the same layers are present in the slider of FIG. 11. The process for forming the slider shown in FIG. 11 is essentially a combination of the processes for the embodiments of FIGS. **7** and **9**, and includes the following steps (in one possible order):

11a. Follow steps **7a-7d** for the embodiment of FIG. **7** to obtain combined layers **36, 84, 82** and **38**.

11b. Follow steps **9a-9c** for the embodiment of FIG. **9** to obtain combined layers **188, 182, 184** and **32**.

11c. The combined layers **36, 84, 82** and **38** (from step **11a** above) are then heat laminated with the second layer **34** in a

heat compression mold. In other words, the bottom-facing surface of the second layer **34** is heat laminated to the upper-facing surface of the third layer **36**.

11d. The combined layers **34, 36, 84, 82** and **38** are heat-pressed in the mold to form the desired product shape.

11e. The mold is then opened, and the combined layers **188, 182, 184** and **32** (from step **11b**) are placed into the mold and heat-pressed on top of the upper-facing layer of the second layer **34**.

11f. The mold is opened and excess material is trimmed away from the edges in the manner illustrated in FIGS. **4A** and **4B**.

FIG. 12 illustrates a modification that can be made to the slider of FIG. **11**, where the binding layers **84** and **184** are again omitted. The process for making the slider of FIG. **12** is the same as described above for the slider of FIG. **11**, except that the bottom-facing surface of the printing layer **182** is directly heat-laminated to the upper-facing surface of the first layer **32**, and the upper-facing surface of the printing layer **82** is directly heat-laminated to the bottom-facing surface of the third layer **36**.

While the description above refers to particular embodiments of the present invention, it will be understood that many modifications may be made without departing from the spirit thereof. The accompanying claims are intended to cover such modifications as would fall within the true scope and spirit of the present invention.

What is claimed is:

1. A method of making a slider having an upper protection layer, an upper printing layer, a first upper layer, a second intermediate layer, a third intermediate layer, a lower printing layer, and a fourth bottom layer, comprising:

- a. printing a graphics pattern on a bottom-facing surface of the lower printing layer;
- b. attaching an upper-facing surface of the lower printing layer to a bottom-facing surface of the third layer;
- c. laminating the bottom-facing surface of the lower printing layer to an upper-facing surface of the fourth layer;
- d. laminating a bottom-facing surface of the second layer to an upper-facing surface of the third layer in a heat-compression mold;
- e. forming a graphics pattern on an upper-facing surface of the upper printing layer;
- f. laminating the protection layer to the upper-facing surface of the upper printing layer;
- g. attaching a bottom-facing surface of the upper printing layer to an upper-facing surface of the first layer;
- h. heat-pressing the combined second, third, lower printing layer and fourth layers in a mold to form a desired shape; and then
- i. heat pressing the combined protection layer, upper printing layer and first layer on top of the second layer inside the mold to form the slider.

2. The method of claim **1**, further including:

forming the fourth layer by a liquid extrusion process.

3. The method of claim **1**, further including:

forming the fourth layer with a mixture of a low density polyethylene and a high density polyethylene.

4. The method of claim **1**, further including:

trimming excess material from the edges of the slider.

5. The method of claim **1**, further including:

providing the second layer with the lowest density; and

providing the fourth layer with the highest density.

6. The method of claim **5**, further including:

providing the first layer with a density that is greater than the density of the third layer; and

providing the third layer with a density that is greater than the density of the second layer.

7. The method of claim 5, further including:

providing the second layer with a density between 30 KG to 60 KG per 1 m³.

8. The method of claim 1, further including:
forming an opening that extends through the first, second, third and fourth layers.
